ATTACHMENT FOR USE WITH BURNING EQUIPMENT

Anthony Milazzo, Brooklyn, N. Y.

Application March 8, 1954, Serial No. 414,908

7 Claims. (Cl. 266—23)

(Granted under Title 35, U. S. Code (1952), sec. 266)

The invention described herein may be manufactured and used by or for the Government of the United States of America for governmental purposes without the payment of any royalties thereon or therefor.

This invention relates to an attachment for use with burning equipment and more particularly it relates to an attachment for use with mechanized burning equipment that permits the completion of a burning operation in one uninterrupted traverse of the burning equipment.

Where the need arises to modify a structural member such as an I-beam by cutting away either part or all of one side or both sides of one of its flanges along the entire length of the beam, resort is usually had to mechanized burning equipment. To perform the burning operation expeditiously, a metal burning torch or a pair of metal burning torches is mounted on a mechanized traverse equipment. The mechanized traverse equipment generally includes a carriage provided with power driving means and further includes a plurality of rollers driven by the power driving means to propel the carriage along the length of the structural member. The metal burning torches are adjustably secured to the carriage. As the carriage moves along the length of the structural member, the metal burning torches are adapted to separate by burning the undesired portion(s) of the beam along its entire length from the main body of the beam. The torches are attached to one end of the carriage. When the mechanized equipment is at the beginning of its traverse which is at one end of the beam, the burning torches are positioned to begin cutting away the undesired portions of the beam beginning at the one end of the beam. However, it is not possible to perform the entire burning operation along the entire length of the beam in one continuous traverse of the carriage. If the carriage were to continue moving when it approached the end of the beam opposite the starting end the carriage would drop right off the end; even at that the torches would still not have completed the burning operation along the entire beam. It is a conventional procedure, at present, to stop the carriage as it approaches the end of the beam, extinguish the cutting torches, take the carriage off the end of the beam, turn the carriage around, and then remount it on the beam so that it is ready to complete the burning operation by starting from the end opposite the starting end and moving toward the starting end. The burning torches thereby are able to complete the burning operation.

This invention marks a departure from the prior art in that it provides an extension adapted to be conveniently attached to the end of a structural beam prior to the beginning of the burning operation. The attachment provides an extension of the supporting surface for the rollers of the mechanized traverse equipment. The attachment has a supporting means at one end and a convenient attaching means at the other end for securing the attachment to the structural member in an aligned relationship therewith. The attachment is designed to accommodate a range of sizes of beams.

2

An object of this invention is to provide an attachment for use with burning equipment.

A further object is to provide an attachment for use with burning equipment that is adapted to eliminate the need for reversal of the burning equipment prior to completion of a burning operation.

A further object is to provide an attachment for use with burning equipment permitting a complete burning operation once the equipment is set up.

10 A further object is to provide an attachment for use with mechanized burning equipment to permit a complete burning operation in one traverse of the burning equipment.

Other objects and many of the attendant advantages of this invention will be readily understood by reference to the following detailed description when considered in connection with the accompanying drawings wherein:

The single figure shows a preferred embodiment of the attachment of this invention partially broken away and secured to one end of a structural member only a part of which is shown on the drawing.

There is shown on the drawing an attachment 10 for use with mechanized metal burning equipment. For purposes of illustration and not in any limiting sense, the attachment 10 is shown secured to one end of an elongated structural I-beam 11, having an upper flange 12; only a small broken away portion of the I-beam 11 is shown on the drawing. The end of the I-beam 11 is not altered in any manner prior to securing the attachment 10 thereto.

The attachment 10 includes an extension 13, preferably in the form of a section of T-beam. The section of T-beam 13 is of a lightweight metal or other strong material. Lightweight material is preferred so that it may be handled easily in transferring it from one workpiece to another workpiece. Aluminum has been found to be suitable. The section of T-beam 13 has a web 14.

Securing means, generally shown at 15, is provided for securing the attachment 10 relative to the beam 11. The securing means 15 includes a right-triangular section of flat plate 16. One of the perpendicular sides of the section of flat plate 16 is welded to the web 14 of T-beam 13 adjacent one end thereof so that the former and the latter are coplanar. The side of the section of flat plate 16 perpendicular to the side welded to the web 14 is aligned with the end of the web. Welded to each surface of the right-triangular section 16 is an attaching means 17. Each attaching means 17 includes a longitudinal leg 21 and a transverse leg 26. Threadedly engaged within tapped holes in the transverse legs 26 are bolts 18, 19, and 20. The clamping bolts are arranged to engage the web of the beam 11 when the latter is disposed in the space between the attaching means 17. Additional bolts 27 are threadedly engaged within tapped openings in the ends of longitudinal legs 21. By virtue of their position, bolts 27 not only engage the web of beam 11 for the purpose of clamping but in addition serve to align the attachment 10 longitudinally relative to beam 11. Set screws 22 are threadedly engaged in tapped holes in transverse legs 26. The set screws 22 serve initially to engage the web of beam 11. Being of the socket type they may be conveniently manipulated simultaneously to align the web 14 of the section of T-beam 13 with the web of beam 11.

Each of the transverse legs 26 is further formed with a cutout 24 adapted to receive the ends of the lower flange of beam 11. By this arrangement it is possible for the attachment 10 to be used with a greater range of sizes of I-beams than would otherwise be possible.

70 Shields 23 are adjustably secured to the longitudinal legs 21 of the attaching means 17. The shields 23 are flat copper members. They are formed with elongated

slots 28. Fastening screws 29 are passed through the elongated slots 28 and are threadedly engaged within the longitudinal legs 21 for retaining the shields 23 in fixed relationship thereto. The elongated slots permit the shields to be adjusted according to the thickness of the web of beam 11.

Since the weight of the attachment 10 plus the weight of a mechanized burning equipment is too heavy for the attaching means 16, an auxiliary support 25 is provided for the attachment 10. The auxiliary support includes a pair of telescoping members 31 and 32 and a thumb screw 33. Telescoping support 25 is pivotally secured to the T-beam 25 by a pivot 34. The thumb screw 33 on the telescoping support 25 permits for adjustment of the supporting end 32.

In operation, the attachment 10 is first brought into position at the end of I-beam 11 manually and then while holding the attachment 10 so that the surface of the flange of the T-beam section 13 is substantially coplanar with the surface of flange 12 of I-beam 11, the set screws 22 are tightened against the web of the I-beam 11. Through simultaneous manipulation of the wrenches engaged in the sockets of the set screws, the end of the web 14 of the section of T-beam 13 is aligned with the web of the I-beam 11. The attachment 10 is then aligned longitudinally with respect to the I-beam 11 by selective tightening of the bolts 27. When the bolts 27 are finally tightened the attachment 10 is partially secured. Subsequently, the bolts 18, 19, and 20 are tightened to finally secure the attachment 10 to the I-beam 11. The copper shields are adjusted by loosening the screws 29 and sliding the shields to their inmost positions abutting the web of the beam 11. As the mechanized burning equipment proceeds along the beam 11 and approaches the end shown on the drawing, one end of the equipment approaches and comes into engagement with the attachment 10. Motion of the mechanized burning equipment continues until the burning operation is completed along the entire length of the beam 11. At that time the mechanized burning equipment is brought to rest entirely on the attachment 10. As the metal burning torches pass over the shields 23 the attaching means 17 is protected against the flame of the torches by the copper shields 23. By this arrangement the burning operation is completed in one traverse of the equipment without the need for additional handling with consequent loss of time.

Obviously many modifications and variations of the present invention are possible in the light of the above teachings. It is therefore to be understood that within the scope of the appended claims the invention may be practiced otherwise than as specifically described.

I claim:

1. An attachment for use in conjunction with metal burning equipment and adapted to be removably attached to an end of a webbed structural beam, said attachment comprising; a T-beam extension of a light weight material such as aluminum; a telescopic support pivotally secured to one end of said extension and adapted, in use, to extend substantially perpendicularly to the length of said T-beam extension and in approximate alignment with the web thereof, and when not in use adapted to be pivoted into a position parallel to the length of said T-beam extension; a right-triangular section of flat plate, one of the perpendicular sides of said right-triangular section welded to the web of said T-beam extension so that said right-triangular section is substantially coplanar therewith and the other perpendicular side is aligned with the end of the web at the end of the T-beam extension opposite the end thereof to which is secured said telescopic support; a pair of identical attaching means, each of said attaching means including a longitudinally extending leg and a transversely extending leg, the transversely extending legs of said attaching means welded to opposite surfaces of said right-triangular section; a bolt threadedly engaged with the free end of each longitudinally extending leg of said attaching means; a set screw threadedly engaged with each transversely extending leg of said attaching means; a plurality of bolts threadedly engaged with each transversely extending leg of said attaching means; the web of a structural beam adapted to be received in the space between said attaching means, the said attachment adapted to be initially aligned with and secured to a webbed beam by means of said set screws, said bolts on the free ends of the longitudinally extending legs of said attaching means subsequently adapted to be tightened against the web of the structural beam for longitudinally aligning and then securing said attachment and finally said bolts in the transversely extending legs firmly securing said attachment to the webbed beam; and copper shields adjustably fastened to said attaching means for protecting the latter from the flame of metal burning equipment.

2. An attachment for use in conjunction with metal burning equipment and adapted to be removably attached to one end of a webbed structural beam, said attachment comprising; a T-beam extension of a lightweight metal such as aluminum; a telescopic support pivotally secured to one end of said extension and adapted, in use, to extend substantially perpendicularly to the length of said T-beam extension and in approximate alignment with the web thereof, and when not in use adapted to be pivoted into a position parallel to the length of said T-beam extension, a right-triangular section of flat plate, one of the perpendicular sides of said right-triangular section of flat plate welded to the web of said T-beam extension so that said right-triangular section is substantially coplanar therewith and its other perpendicular side is aligned with the end of the web at the end of the T-beam extension opposite the end thereof to which is secured said telescopic support; a pair of identical attaching means, each of said attaching means including a longitudinally extending leg and a transversely extending leg, the transversely extending legs of said attaching means welded to opposite surfaces of said right-triangular section; a bolt threadedly engaged with the free end of each longitudinally extending leg of said attaching means; a set screw threadedly engaged with each transversely extending leg of said attaching means; a plurality of bolts threadedly engaged with each transversely extending leg of said attaching means; the web of a structural beam adapted to be received in the space between said attaching means, the said attachment adapted to be initially aligned with and secured to a webbed beam by means of said set screws, said bolts on the free ends of the longitudinally extending legs of said attaching means subsequently adapted to be tightened against the web of the structural beam for longitudinally aligning and then securing said attachment and finally said bolts in the transversely extending legs firmly attaching said attachment on the webbed beam; and copper shields adjustably fastened to said attaching means for protecting the latter from the flame of metal burning equipment.

3. An attachment for use in conjunction with metal burning equipment and adapted to be removably attached to one end of a webbed structural beam, said attachment comprising; a T-beam extension of a lightweight metal such as aluminum; a support pivotally secured to one end of said extension and adapted in use to extend substantially perpendicularly to the length of said T-beam and in approximate alignment with the web thereof, and when not in use adapted to be pivoted into a position parallel to the length of said T-beam extension; a section of flat plate, said section of flat plate being formed with at least two perpendicular sides, one of the perpendicular sides of said section of flat plate welded to the web of said T-beam extension so that said section is substantially coplanar therewith and the other perpendicular side is

4. An attachment for use in conjunction with metal burning equipment and adapted to be removably attached to one end of a webbed structural beam, said attachment comprising; a T-beam extension of a lightweight metal such as aluminum; a support pivotally secured to one end of said extension and adapted in use to extend substantially perpendicularly to the length of said T-beam and in approximate alignment with the web thereof, and when not in use adapted to be pivoted into a position parallel to the length of said T-beam extension; a section of flat plate, said section of flat plate being formed with at least two perpendicular sides, one of the perpendicular sides of said section of flat plate welded to the web of said T-beam extension so that said section is substantially coplanar therewith and the other perpendicular side is

aligned with the end of the web at the end of the T-beam extension opposite the end thereof to which is secured said support; a pair of identical attaching means, each of said attaching means including a longitudinally extending leg and a transversely extending leg, the transversely extending legs of said attaching means welded to opposite surfaces of said section of flat plate; a bolt threadedly engaged in the free end of each longitudinally extending leg of said attaching means; a set screw threadedly engaged in each transversely extending leg of said attaching means; a plurality of bolts threadedly engaged in each transversely extending leg of said attaching means; the transversely extending legs of said attaching means adapted to receive in the space therebetween the web of a structural beam; the said attachment adapted to be initially aligned with and secured to a webbed beam by means of said set screws, said bolts on the free ends of the longitudinally extending legs subsequently adapted to be tightened against the web of the structural beam for longitudinally aligning and then partially securing said attachment, and finally said bolts in the transversely extending legs finally securing said attachment on the webbed beam.

4. An attachment for use in conjunction with metal burning equipment and adapted to be removably attached to one end of a webbed structural beam such as an I-beam, said attachment comprising; a T-beam extension; a support pivotally secured to one end of said extension and adapted, in use, to extend substantially perpendicularly to the length of said T-beam extension and in approximate alignment with the web thereof, and when not in use is adapted to be pivoted into a position parallel to the length of said T-beam extension; a section of flat plate welded to the web of said extension substantially coplanar with the web thereof and at the end opposite that to which is secured said support; a pair of attaching means, each of said attaching means including a longitudinally extending leg and a transversely extending leg, the transversely extending legs of said attaching means welded to opposite surfaces of said section of flat plate; means on said attaching means for securing said attachment to one free end of a webbed structural beam and in alignment therewith; and shield means for protecting said attaching means from the flame of metal burning torches.

5. An attachment for use in conjunction with metal burning equipment and adapted to be removably attached

45

to one end of a webbed structural beam, said attachment comprising; an extension formed with a surface adapted to be aligned coplanar with the outside surface of a flange of a structural beam, means fixed on one end of said extension and adapted for attaching said extension to the structural beam in longitudinal alignment therewith; and shields mounted on said means and located between said means and the aforementioned surface of said extension for protecting said means from the flame of metal burning equipment.

10 6. An attachment for use in conjunction with metal burning equipment and adapted to be removably attached to one end of a webbed structural beam such as an I-beam, said attachment comprising; a T-beam extension; a section of flat plate welded to the web of said extension substantially coplanar with the web thereof and at one end thereof; a pair of attaching means, each of said attaching means including a longitudinally extending leg and a transversely extending leg, the transversely extending legs of said attaching means welded to opposite surfaces of said section of flat plate; means on said attaching means for securing said attachment to one free end of a webbed structural beam and in alignment therewith; and shield means mounted on said attaching means for protecting said attaching means from the flame of metal burning torches.

20 7. An attachment for use in conjunction with metal burning equipment and adapted to be removably attached to one end of a webbed structural beam, said attachment comprising; an extension formed with a surface adapted to be aligned coplanar with the outside surface of a flange of a structural beam; a support secured to one end of said extension to extend substantially perpendicularly to the length of said extension; means fixed on the opposite end of said extension and adapted for attaching said extension to the structural beam in longitudinal alignment therewith; and shields mounted on said means and located between said means and the aforementioned surface of said extension for protecting said means from the flame of metal burning equipment.
